(57) **CLAIM**

The ornamental design for a kitchen tool elevator, as shown and described.

DESCRIPTION

FIG. 1 is a perspective view of the kitchen tool elevator showing my new design.

FIG. 2 is a side view thereof.

FIG. 3 is a bottom view thereof.

FIG. 4 is a top view thereof.

FIG. 5 is a front view thereof; and,

FIG. 6 is a back view thereof.

The broken lines in the drawings illustrate portions of the kitchen tool elevator which form no part of the claimed design.
